CLAIM

The ornamental design for a seat, as shown and described.

DESCRIPTION

FIG. 1 is a perspective view of a seat according to the present invention;

FIG. 2 is a front view of the seat of FIG. 1;

FIG. 3 is a rear view of the seat of FIG. 1;

FIG. 4 is a top view of the seat of FIG. 1;

FIG. 5 is a bottom view of the seat of FIG. 1; and,

FIG. 6 is a side view of the seat of FIG. 6.

The seat is symmetrical about a vertical axis and the side views are substantially identical.
